LIFEBOAT LAUNCHING APPARATUS

John L. Hyland, New York, N. Y.

Application November 26, 1928
Serial No. 321,988

7 Claims. (Cl. 9—22)

This invention relates to life boat launching apparatus, and the primary object thereof is to provide improved means for effecting safe and expeditious launching of the life boat.

5 A further object of the invention is to provide novel means for moving the life boat to a position beyond the side of the vessel and at the same time for effecting vertical movement of the life boat to offset listing.

10 A further object of the invention is to provide means for lowering the life boat solely by the weight thereof, and to also provide braking means for controlling the lowering of the boat.

A still further object of the invention is to provide a series of life boats which are superposed and which can be independently lowered.

15 A still further object of the invention is to provide a life boat having a single mounting which enables the life boat to be swung to a position beyond the side of the vessel by a simple turning movement thereof.

20 A still further object of the invention is to provide a launching device which is at all times ready for swinging of the boat to a launching position with respect to the vessel, and which eliminates the use of block and tackle, pulleys and the like, and in which the life boat is launched by a single lowering device carried by the boat itself.

25 The invention has still further and other objects, which will be later set forth and manifested in the course of the following description.

In the drawing:—

Fig. 1 is a side elevation of a boat in accordance 30 with the present invention showing same mounted on the deck of a vessel, the deck being shown in section;

Fig. 2 is a side elevation partly broken away and in section showing the boat during lowering 40 thereof;

Fig. 3 is a fragmentary detail view of the raising and lowering means carried by the boat;

Fig. 4 is an enlarged detail view of a part of the raising and lowering device;

45 Figs. 5 and 6 are sections on lines 5—5 and 6—6 of Fig. 3;

Fig. 7 is a view similar to Fig. 1 showing a series of life boats and their mounting means, and

50 Fig. 8 is a view similar to Fig. 4 of a modified form of the invention.

In proceeding in accordance with the present invention a threaded shaft or rod 1 is employed which is rigidly secured to the deck of a vessel 55 shown in part at 2. A substantially U-shaped

davit 3 is provided with a threaded socket receiving the threaded shaft 1, the davit having horizontal portions 4 which overlie the lifeboat and which portions 4 at their centers have cables 5 connected thereto as shown in Fig. 2. The opposite ends of the cables are connected to a horizontal rotary sleeve 6, (see Fig. 3) the sleeve having one end internally threaded as shown in Fig. 4 and engaging the threads 7 of a horizontal rod 8. The rod 8 is rigidly secured at its opposite ends to the ends of the life boat 9 so that the sleeve when rotated will move longitudinally of the rod. Tubular guides 10 may be employed and are also rigidly secured to the life boat for the purpose of guiding the cables during winding thereof on the sleeve 6.

As shown in Figs. 2, 3 and 4, a single sleeve 6 is employed. However, as shown in Fig. 8, if desired the rod 8' may be provided with opposed threaded portions 11 and a pair of sleeves 12 employed, which latter are independently movable on the rod, allowing separate movement of each sleeve.

In order to control the rotation of the sleeve 6 or the sleeves 12 a brake may be employed which 80 consists of a block 13 apertured to receive the sleeve therethrough and which is drawn into frictional engagement with the sleeve by means of a threaded member 14 having a handle 15 to enable turning thereof. Obviously, however, any form 85 of braking device can be employed and if desired, for example, the sleeve may be formed with apertures 16 to receive rods or handles, not shown, so as to control the rotation of the sleeve.

As shown in Fig. 7, a series of life boats 9' may 90 be arranged in superposed order and are mounted on a single rod 16' to turnably support the davits 3' as described in connection with Fig. 1. The raising and lowering devices in this form of the invention are precisely as above described.

In operation it will be seen that the davits 3 or 3' are at all times pivotally related to the vessel so as to be capable of being instantly swung around on their pivots 1 or 16' to dispose the boats in launching position. Thus a single 100 pivot is employed for swinging the entire life boat to its outer position. The seamen, when the boat is in its outer position at the side of the deck, operate the handle 15 to release the brake on the sleeve 6 so as to enable the sleeve 6 to rotate and 105 by virtue of the weight of the boat and its occupants, the boat is lowered and at any desired speed regulated by the screw 14. The rotary and longitudinal movement of the sleeve 6 progressively brings the several convolutions of the sus- 110

sension cables 5 to a position in alinement with the tubular guides 10.

In the modification shown in Fig. 7, it will be seen that either one of the boats 9 may be swung 5 to its outer position independently of the other, and that the two boats may be thus moved to their outer positions without either interfering with the other, the rod 16' affording a common pivotal support or mounting for each or both of 10 the two boats.

The invention may be practiced by having the cables 5 connected to the sleeve 6 so that when the same have been completely unwound therefrom and the boat is in the water, the cables will 15 be automatically disconnected from the sleeve, leaving the boat free, or the cable may be provided with separable links at any desired point, so that when the boat reaches the water, the links 20 may be readily disconnected, for example a pin 18 may be attached to the sleeve and the rope looped over it at its end, the loop being freely passed over the pin so that when it is completely unwound, it will automatically free itself from 25 the latter.

In raising, either following launching drills, or otherwise, the sleeve is rotated to wind the 30 cables thereon, which is accomplished by the seamen in the life boat, for instance by inserting handles in the apertures 16. In this operation, the sleeve progressively slides in addition to rotating so as to regularly lay the cable coils thereon in 35 abutting engagement as shown in Fig. 3.

What is claimed is:—

1. A life boat launching apparatus, including 35 a vertical threaded shaft, means to rigidly secure said shaft to a vessel, a substantially U-shaped davit having a threaded socket receiving the shaft and having horizontal portions at the ends of its arms, a life boat, raising and lowering 40 means carried by the boat, and cables connected to the centers of said horizontal portions and to the raising and lowering means.

2. A life boat launching apparatus including a 45 vertical threaded shaft, means to rigidly secure said shaft to a vessel, a davit threaded into en-

gagement with said shaft, a life boat, raising and lowering means carried by the boat, and cables connected to the davit and to the raising and lowering means.

3. In combination with a plurality of superposed davits, means for mounting the davits for horizontal rotary movement, a series of life boats each having raising and lowering means therein, and suspension means for each boat connected to the respective davits and to the raising and lowering means of the boats. 80 85

4. In a life boat launching apparatus, a vertical threaded shaft, means to secure the shaft to a vessel, a series of superposed davits threadedly connected to the shaft for simultaneous horizontal rotary and vertical movements, and a life boat connected to each of the davits. 90

5. The combination with a davit, of a lifeboat having a shaft mounted therein, a sleeve fitted over the shaft, and having screw threaded engagement therewith, said shaft extending entirely through the sleeve and a cable having one end secured to the davit and the opposite end coiled about the sleeve, and a brake applied directly to the sleeve to limit and regulate the uncoiling of 100 the cable. 95

6. In lifeboat launching apparatus, the combination of a shaft having both ends thereof fixed, a sleeve journaled on the shaft for rotation thereon, said sleeve having a screw-threaded connection with the shaft to cause lengthwise movement thereof on rotation, at least two cables wound on the sleeve in spaced relation, and means for controlling the rotation of the sleeve. 105

7. In lifeboat launching apparatus, the combination in a lifeboat, of a shaft having both ends thereof fixed to the lifeboat against rotation, a sleeve journaled on the shaft for rotation thereon, said sleeve having a screw-threaded connection with the shaft to cause lengthwise movement thereof on rotation, at least two lowering cables wound on the sleeve in spaced relation, and means engaging the sleeve, for controlling the rotation thereof relative to the shaft. 110 115
